UNITED STATES PATENT OFFICE.

CHARLES T. MASON, OF SUMTER, SOUTH CAROLINA, ASSIGNOR TO
SUMTER TELEPHONE MANUFACTURING COMPANY, OF SUMTER,
SOUTH CAROLINA.

TELEPHONE-RECEIVER.

No. 823,061.

Specification of Letters Patent.

Patented June 12, 1906.

Application filed March 17, 1905. Serial No. 250,524.

To all whom it may concern:

Be it known that I, CHARLES T. MASON, a citizen of the United States, residing at Sumter, in the county of Sumter and State of South Carolina, have invented new and useful Improvements in Telephone-receivers, of which the following is a specification.

This invention is an improved telephone-receiver characterized by the fact that the magnet structure is molded in a soft-metal section which is screwed and cemented at adjustment in a cup forming part of the receiver-casing, whereby the magnet is held rigidly therein, the casing being completed by a removable cap, which also clamps the diaphragm, and a removable handle or shell.

A further novel feature is embodied in means for removably supporting the coils and for connecting the same to the terminals of the receiver-cord.

In the accompanying drawings, Figure 1 is a central longitudinal section of the receiver with the parts assembled. Fig. 2 is a front end view with the ear-cap and diaphragm removed. Fig. 3 is a sectional view of the magnet structure. Fig. 4 is a perspective view of one of the coils.

Referring specifically to the drawings, B indicates a combined cup and casing section made of rubber or other composition. This cup B is exteriorly threaded at the front end to receive the screw-cap A, by which the diaphragm a is clamped to the front end of the cup. The casing is completed by the rear or handle section C. The section B supports the magnet structure and forms a rigid and permanent union therewith and avoids the necessity for separate cup and casing sections, since it forms both the cup and part of the casing.

The magnet structure comprises the horse-shoe-magnet j and the pole-pieces b and fiber block i, clamped between the front ends of the magnet by a bolt f, and said fiber piece carries the terminals n, to which the receiver-cord h is attached, the terminals being held by binding-screws l, which are connected by

wires r to the coils. Around the magnet structure is molded a block e, of soft metal or the like having a low fusing-point, said magnet structure being thereby rigidly fixed therein. The block e is exteriorly threaded and is screwed into and through the bottom of the cup B, thereby having a projecting portion G, onto which the handle C is screwed.

In assembling the parts a small space p is left between the ledge at the front end of the block e and the bottom of the cup to allow of the adjustment of the magnet structure to bring the pole-piece in proper relation to the face of the cup, and consequently to the diaphragm. This space is filled by a suitable cement, which also enters between the threads. While the cement is soft such adjustment as is necessary may be made, after which the cement sets and hardens and holds the magnet structure in permanent adjustment. The coils c are removably held on the pole-piece in the cup, the lower end plate of each coil having a perforated ear to receive a screw k to hold the coil upon the block e. This block has holes h' for the connecting-wires. The screws l allow the coils to be disconnected and removed without unsoldering any wires. This is advantageous when the coils have to be replaced for any reason, as when burned out.

It is desirable in receivers to have the magnet structure rigid with the casing. This is conveniently effected by the invention herein shown, because the magnet structure is molded in the block e, and this block becomes rigidly fixed to the casing-section B by screwing and cementing therein, and the block also serves to hold the handle and cup together.

What I claim as new, and desire to secure by Letters Patent, is—

In a telephone-receiver, the combination with a magnet structure, of a threaded block molded around the front end of the magnet and the rear ends of the pole-pieces, and having a shoulder around its front end, a cup-section forming the middle part of the casing and in which the block is screwed, leaving a space between said shoulder and the bottom

of the cup, in which space cement is placed to permanently fix the block in the cup, coils on the pole-pieces, having terminals which extend through holes in the block, and a handle which incloses the rear end of the magnet structure and is screwed on the rear end of the block.

In testimony whereof I have signed my name to this specification in the presence of two subscribing witnesses.

CHARLES T. MASON.
